ELECTRIC LAMP FIXTURE

Alphonse F. Pieper, Brighton, N. Y.

Application April 9, 1948, Serial No. 20,129

7 Claims. (Cl. 240—51.12)

1

This invention relates to an electric lamp fixture, with reference more particularly to a structure for supporting a pair of circular lamps of different diameters one within the other in planes at right angles to one another or in other angular relationship and it has for its purpose to provide a simple, practical and efficient structure that is pleasing to the eye and which permits two such lamps to be readily positioned for use or removed easily for replacement.

More particularly the invention has for its purpose to afford a fixture comprising a housing with four radial supports, two for each lamp at opposite points thereof, and so constructed as to enable readily positioning the conducting wires leading to the lamp sockets within the housing and permitting a simple and quick assembly of the parts.

Another object of the invention is to afford a housing for the purpose described above that permits easy attachment on a lamp standard with an ornament and shade-supporting post detachably arranged thereabove, and includes four supports at least, two of which are hollow to receive the conducting wires leading to the lamp sockets which are secured in the housing.

Still an additional object of the invention is to provide a fixture with a housing having four radial supports and consisting of two sections which are separably held together to enclose the conducting wires and form the supports for the lamps, two of the supports being provided with yieldable gripping members that assist in holding the sections together and retain the lamps, the gripping members being movable to permit positioning the lamps or removing them from the fixture.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in front elevation, partially in section, showing a preferred embodiment of the invention as incorporated in a fixture for supporting two circular fluorescent lamps of different diameters in perpendicular planes;

Fig. 2 is a view similar to Fig. 1, somewhat reduced in size, of the front section of the housing, the other section with the switch and conducting wires being removed;

Fig. 3 is a view in rear elevation looking in the opposite direction of Figs. 1 and 2, showing the rear section of the housing;

Fig. 4 is a top view;

Fig. 5 is a view in side elevation;

2

Fig. 6 is an enlarged detail horizontal sectional view on line 6—6 of Fig. 1;

Fig. 7 is an enlarged detail horizontal sectional view on line 7—7 of Fig. 1, and

Fig. 8 is an enlarged detail horizontal sectional view on line 8—8 of Fig. 1.

The invention comprises in general a housing which encloses the conducting wires and comprises two separable parts or sections, each of which sections includes a central portion for connection with the lamp standard from which the conducting wires lead to said central portion and two pairs of oppositely extending radial arms, the arms of each pair being of different length, preferably in alinement, and serving to support a circular fluorescent lamp, and the arms of one pair being somewhat shorter than the corresponding arms of the other pair so as to arrange a lamp of smaller diameter within a larger diameter lamp.

Referring more particularly to the drawings in which like reference numerals refer to the same parts throughout the several views, the housing which includes hollow arms for enclosing the conducting wires leading from the lamp standard to the lamps, preferably comprises one section including a dished and generally circular central portion 1, see Fig. 2, with a pair of radial oppositely disposed arms 2 and 3, and a pair of radial oppositely disposed arms 4 and 5, preferably integral with the central portion 1 and arranged in planes at angles to one another as shown.

The radial arms 2 and 4 are of hollow cross-section for a purpose that will appear presently, and the arms 2 and 3 which are preferably aligned are somewhat longer than the arms 4 and 5 respectively, whereby the arms 4 and 5 may support a circular lamp positioned within a lamp arranged on the arms 2 and 3, and the arms 2 and 4 are longer than the arms 3 and 5 in order to enable positioning two lamps of different diameters one within the other in perpendicular planes and arranged so that the diametric center of one lamp coincides with the diametric center of the other lamp at x, as indicated in Fig. 1.

In order to secure the housing on a lamp standard, the section just described includes within its central portion a separable attaching plate 6 provided with oppositely disposed integral collars 7 and 8 which fit snugly in recesses provided in the central portion 1 and in corresponding recesses provided in the other section to be described presently and are thus interlocked with the central portion of the housing. The collar 8 is threaded interiorly to engage the lamp standard or post 9 on which it is mounted, while 10 designates a rod adapted to engage a threaded opening in the collar 7 and to support a lamp shade as usual. In order to secure the housing tightly on the plate 6, the latter is provided with

opposite integral bosses 11 and 12 which have threaded openings extending therethrough to receive fastening screws that secure the two sections of the housing tightly to the plate 6 and thus hold the entire assembly in rigid relationship.

The other section of the housing includes a central portion 13, see Fig. 3, oppositely extending arms 14 and 15 that lie against the arms 4 and 5 respectively when assembled, and oppositely extending arms 16 and 17 that lie against the arms 2 and 3 respectively when assembled; the arms 14 and 16 being of hollow cross-section and similarly formed to the arms 2 and 4, while the arms 15 and 17 are formed similarly to the arms 5 and 3 respectively.

The housing section just described also includes semi-circular recesses 18 that receive the adjacent portions of collars 7 and 8 of the plate 6 when the sections of the housing are secured together, the sections being held in assembled relation by means of fastening screws 19 and 20 which extend through openings in the central portion 13 of one section of the housing and engage threaded openings in the bosses 11 and 12 of the plate 6 on one side thereof while fastening screws 21 and 22 extend through the central portion 1 of the other section of the housing and engage the threaded bosses 11 and 12 from the opposite side, see Fig. 8, and in this manner the two sections of the housing are held securely together at their central portions and tightly engaged with the fastening plate 6 that is threaded on the lamp standard.

The front section of the housing which includes the central portion 13 has an opening provided in the outer wall of said central portion to receive an electric switch 23 which is fixedly secured therein and may be controlled by a pull chain indicated at 24 and is of any conventional or standard type, the particular construction of the switch constituting no part of the invention, and the conducting wires 25 extend through the hollow lamp standard 9 and thence into the central portion of the housing and to the switch 23 from which they extend through the upper hollow arms of the housing to the lamp sockets indicated at 26 which are secured to the conductors in the usual manner. The lamp sockets 26 are of any suitable plastic or insulating material, being arranged in recesses provided in the arms, see Fig. 6, and include bottom flanges or shoulders 28 that seat in the recesses in the arms 2 and 16, and 4 and 14, respectively, so that when the housing sections are secured together, the portions of the opposed arms which overlie the shoulders 28 lock the sockets 26 in place and hold them securely between the sections of the housing, as shown in Figs. 1 and 3.

The opposite arms of the housing constituting the upper supports are secured together by means of fastening screws 29 and 30 respectively, which extend through openings in one of the sections and engage threaded openings in the other section to hold the arms in tight relationship, as illustrated in Fig. 6, with the lamp socket arranged therebetween. The arms 3 and 17 are additionally secured by a fastening screw 31, see Fig. 1, which extends through the arm 17 and threadedly engages the opposed arm 3.

In order to position the lamps, which are of conventional form, the upper arms 2, 4, 14 and 16 are provided with upstanding inner extensions 32 shaped to afford curved seats 33 against which the circular lamp 34 rests when its plug or con-

nexion is engaged with the socket 26, in the manner illustrated in Fig. 1, while the opposite portion of the lamp is retained in position by a yieldable retaining member that will now be described.

Each pair of arms 3, 17, and 5, 15, which are in contact or opposed relationship to form a support when the parts are assembled, is provided with a yieldable gripping member including a curved lamp-gripping surface 35. Each gripping member is recessed to provide opposite side walls 36 which straddle the ends of the arms or support, as shown in Figs. 1 and 7, and are mounted pivotally thereon by means of a friction pin 31. The gripping member includes a bottom portion terminating in a surface 38 which engages the ends of the arms and limits outward movement of the gripping member, the latter being movable inwardly against the tension of a spring 39 which normally holds the gripping member in its outermost position. The spring 39 is arranged in a recess provided in the gripping member, one end of the spring being seated at the bottom of the pocket and the other end of the spring being preferably seated around the head of a screw 41 that is secured in an opening formed in the housing, and 42 designates a piece of any suitable soft fabric secured to the engaging face of the gripping member for contacting the surface of the lamp to protect the latter. By removing the friction pins 31 and the fastening screws described above, the gripping members can be removed and the housing sections separated to permit access to the interior of the housing and to the conducting wires and switch, which are secured in place before fastening the housing sections together.

A circular lamp is positioned on the supports by first arranging it over the curved seat 33 on an upper arm, bringing the lamp bodily downwardly so that its contacts are moved into engagement with the socket 26 while at the same time the corresponding yieldable retaining member is pushed inwardly against the tension of its spring 39 as far as it is permitted to go by the inner edge of its top wall. Thus the adjacent or lower part of the circular lamp can be moved downwardly to clear the outer end of the retaining member, and when the lamp is in its lowermost position, the retaining member is released and assumes the position illustrated in Fig. 1, to hold the lamp in fixed relationship to the socket in the upper arm. To remove a lamp, the reverse operation takes place, namely, the gripping member is pushed inwardly against the tension of its spring and the lower portion of the lamp can then be elevated until it clears the gripping member whereupon the lamp can be moved bodily upwardly away from its socket 26.

The operation of positioning or removing each of the two lamps is the same, the only difference being that one lamp is of less diameter than the other and therefore arranged within the diameter of the larger lamp, as shown in Fig. 1, from which it will be observed that the supports or arms extend a greater distance above than below the central portion of the housing. As a result of this arrangement, when two lamps of different diameters are positioned, the diametric center of one lamp coincides with the diametric center of the other lamp, thus affording a symmetrical and the most effective arrangement of two such lamps.

While the invention has been described with reference to the particular detailed arrangement shown, it is not confined to the exact structure

herein disclosed, and this application is intended to cover such modifications or departures as may come within the purposes of the improvement or the scope of the following claims.

I claim:

1. A fixture for a pair of circular lamps of different diameters comprising a housing having two pairs of supports of different lengths which hold the lamps one within the other and enclose the conducting wires, said housing consisting of two separable sections each of which includes a central dished portion and arms extending radially therefrom of hollow cross-section, and fastening means holding the sections together, the arms of two of said supports having curved seats with plug-engaging sockets and the arms of the other supports having spring-actuated yieldable gripping members pivoted on the arms and having curved surfaces engaging the adjacent portions of the lamps and opposite side walls that straddle the arms of said supports and engage the outer surfaces of said arms.

2. A fixture for a pair of circular lamps of different diameters comprising a housing having two pairs of supports of different lengths which hold the lamps one within the other and enclose the conducting wires, said housing consisting of two separable sections each of which includes a central dished portion and arms extending radially therefrom of hollow cross-section, the upper support of each pair extending a greater distance above than below said central portion, and fastening means holding the sections together, the arms of two of said supports having curved seats with plug-engaging sockets and the arms of the other supports having spring-actuated yieldable gripping members pivoted on the arms and having curved surfaces engaging the adjacent portions of the lamps and opposite side walls that straddle the arms of said supports and engage the outer surfaces of said arms.

3. A fixture for a pair of circular lamps of different diameters comprising a housing having two pairs of supports of different lengths which hold the lamps one within the other and enclose the conducting wires, said housing consisting of two separable sections each of which includes a central dished portion and arms extending radially therefrom of hollow cross-section, a fastening plate arranged in the central portion of the housing and having an interiorly threaded collar attachable to a lamp standard, the collar being interlocked with openings formed in the central portions of the sections, bosses on said plate having threaded openings therein, and fastening screws extending through said central portions of the sections from opposite sides and engaging said threaded openings in the bosses.

4. A fixture for a pair of circular lamps of different diameters comprising a housing having two pairs of supports of different lengths which hold the lamps one within the other and enclose the conducting wires, said housing consisting of two separable sections each of which includes a central dished portion and arms extending radially therefrom of hollow cross-section, a fastening plate arranged in the central portion of the housing and having interiorly threaded collars at top and bottom, said collars being attachable to a shade-supporting post and to a lamp standard respectively, the collars being interlocked with openings formed in the central portions of the sections, bosses on said fastening plate hav-

ing threaded openings therein, fastening screws extending through said central portions of the sections from opposite sides and engaging said threaded openings in the bosses, and a switch mounted in the central portions of one of said sections.

5. A fixture for a pair of circular lamps of different diameters comprising a housing having two pairs of supports of different lengths which hold the lamps one within the other and enclose the conducting wires, said housing consisting of two separable sections each of which includes a central dished portion and arms extending radially therefrom of hollow cross-section, fastening means holding the sections together, two of said arms having curved seats with plug-engaging sockets and the other of said arms having spring-actuated yieldable gripping members with curved surfaces engaging the adjacent portions of the lamps, each of said gripping members including side walls which straddle said arms and hold them in engagement, a bottom wall that limits its outward movement, a spring positioned in a recess in the gripping member with one end engaging the bottom of the recess, and a projection on the housing adjacent to the other end of the spring engaging the latter.

6. A fixture for a pair of circular lamps of different diameters comprising a housing having two pairs of supports of different lengths which hold the lamps one within the other and enclose the conducting wires, said housing consisting of two separable sections each of which includes a central dished portion and arms extending radially therefrom of hollow cross-section, fastening means holding the sections together, and lamp-engaging sockets mounted at the upper ends of the arms between said sections, each socket including a peripheral shoulder and the sections including recesses which accommodate the sockets and flanges which overlie said shoulders and anchor each socket in its arm.

7. A fixture for a pair of circular lamps of different diameters comprising a housing having two pairs of supports of different lengths which hold the lamps one within the other and enclose the conducting wires, said housing consisting of two separable sections each of which includes a central dished portion and arms extending radially therefrom of hollow cross-section, the upper support of each pair extending a greater distance above than below said central portion, a fastening plate arranged in the central portion of the housing and having an interiorly threaded collar attachable to a lamp standard, the collar being interlocked with openings formed in the central portions of the sections, bosses on said plate having threaded openings therein, and fastening screws extending through said central portions of the sections from opposite sides and engaging said threaded openings in the bosses.
